BUILDING AND FLOOR FOUNDATION

Herbert J. von Rosenberg, San Antonio, Tex.

Application May 31, 1941, Serial No. 396,112

6 Claims. (Cl. 72—77)

This invention relates to building foundations. At the present time in preparing the foundation for a building, particularly where there is no cellar under the building, channels are formed in the ground for receiving the grade beams and in order to provide for the proper formation of the beam these channels are made wide and deep enough to receive forms on three faces of the beams, which are later removed and the intervening space caused by removal of the forms is filled in with dirt. Where the grade beam is formed in this manner the bottom of the beam contacts directly with the earth channel or the back-filled earth, and the moisture from rain or other sources causes the earth to swell exerting vertical pressure on the beam bottom and frequently cracks the beam.

In addition to the foregoing, the filling in of the space occupied by the form permits the surface moisture to flow down alongside the beam and thence into the column footing excavation, thereby softening the earth supporting the column and causing settlement.

It is, therefore, an object of this invention to provide a preformed soffit construction, which is adapted to be placed beneath the grade beam so as to provide a dead air space below the beam in order that the bottom of the beam will be held out of contact with the earth and provide a space to receive the expanded earth.

Another object of this invention is to provide a grade beam support in the form of a precast soffit which may be placed in a channel formed in the earth which is only sufficiently large to receive the soffit, so that no subsequent filling in is necessary and the surface moisture cannot enter beneath the beam. With a construction of this kind the channel above the precast soffit may be made only sufficiently wide to permit the sides of the channel to constitute the form of the grade beam, although if desirable plywood form or other elements may be placed along the sides of the channel and such elements gradually removed as the concrete for the beam is poured. In this manner the grade beam will entirely fill the channel above the soffit so that no surface moisture will be able to flow down the outer side of the beams. With a construction of this kind considerable economy results from the reduced size of the grade beam channel, and the elimination of forms below grade, and there is no possibility of any vertical pressure being exerted on the beam by swelling of the ground below the beam. Any swelling of the ground beneath the soffit will occur in the closed

chamber formed by the soffit so that such swelling of the ground will not exert any vertical pressure on either the soffit or the beam.

A further object of this invention is to provide an improved foundation or support for a floor structure whereby the floor may be formed as a concrete slab and either closed or open air spaces or channels formed beneath the floor. These spaces or elements may be ventilated or 10 be used as a means for heating the floor, or they may be used as dead air spaces for insulating the floor.

A further object of this invention is to provide an improved floor foundation so that air spaces 15 will not only be formed below the floor, but the floor will be tied or locked to the channel forming support and the effective depth of the floor slab will be materially increased and self-supporting from one beam to another.

20 A further object of this invention is to provide an improved floor foundation which is so constructed as to not only provide channels beneath the floor, but provide a flat surface constituting a lower form or support for the rough 25 or finished floor.

To the foregoing objects and to others which may hereinafter appear, the invention consists of the novel construction, combination and arrangement of parts as will be more specifically 30 referred to and illustrated in the accompanying drawings, wherein are shown embodiments of the invention, but it is to be understood that changes, variations and modifications may be resorted to which fall within the scope of the invention as claimed.

In the drawings:

Figure 1 is a vertical section of a soffit construction according to an embodiment of this invention having a grade beam mounted thereon,

40 Figure 2 is a perspective view of an intermediate soffit showing the soffit in an inverted position for facility of reference.

Figure 3 is a perspective view of an end soffit with the soffit in an inverted position as may be required for beams intersecting girders or columns at a level above the lowest beam or girder,

45 Figure 4 is a vertical section of a modified form of soffit,

50 Figure 5 is a perspective view of the soffit shown in Figure 4,

Figure 6 is a vertical section of a foundation construction embodying a grade beam soffit similar to that shown in Figure 1 and including an improved floor supporting means,

Figure 7 is a perspective view of the floor supporting means shown in Figure 6,

Figure 8 is a vertical section of a foundation embodying a further construction of floor supporting means.

Figure 9 is a fragmentary vertical section of a foundation embodying the soffit shown in Figures 4 and 5 and including an improved floor supporting means,

Figure 10 is a perspective view of a channeled tile adapted for use in a floor supporting construction,

Figure 11 is a fragmentary vertical section of a foundation embodying a further form of floor supporting means,

Figure 12 is a fragmentary vertical section of a foundation including a further form of floor supporting means,

Figure 13 is a perspective view of one of the floor supporting elements shown in Figure 12,

Figure 14 is a vertical section of a soffit structure similar to that shown in Figure 10,

Figure 15 is a vertical section of a further modified form of soffit structure,

Figure 16 is a vertical section of a further modified form of soffit structure,

Figure 17 is a vertical section of a further modification of the soffit structure shown in Figure 10,

Figure 18 is a further modification of soffit structure,

Figure 19 is a further modification of soffit structure similar to that shown in Figure 15,

Figure 20 is a further modification of soffit structure,

Figure 21 is a further modification of the soffit structure shown in Figure 20,

Figure 22 is a further modification of soffit structure, and

Figure 23 is a further modification of soffit structure similar to that shown in Figures 15 and 19.

Referring to the drawings and first to Figures 1 to 3 inclusive, the numeral 15 designates a channel or trench which is dug in the ground for the desired depth in order to receive concrete or the like for construction of a grade beam. The channel or trench 15 is formed with vertically disposed parallel sides and a horizontally disposed bottom 16. In order to provide a means whereby the grade beam 17, which is formed in the trench or channel 15, may be supported in upwardly spaced relation to the bottom 16 of the trench for the purpose of preventing any vertical pressure being exerted on the beam 17 due to swelling of the ground under moisture conditions, I have provided a soffit generally designated as 18.

The soffit 18 is U-shaped in transverse section and includes vertically disposed side wall forming members 19 and 20, which have vertical outer side faces 21 and 22 respectively. The inner face of the side wall 19 is upwardly and may be inwardly inclined, as at 23, and the inner face 24 of the side wall 20 may be also upwardly and inwardly inclined. The top wall or web 25 is substantially of uniform thickness throughout its width and length and is formed or cast integrally with the side wall members 19 and 20. The upper face 26 of the top wall 25 is disposed at right angles to the outer surfaces 21 and 22 and the bottom of the grade beam 17 is adapted to rest on the upper surface 26 of the top wall 25.

The bottom faces 27 and 28 of the side wall members 19 and 20 are adapted to rest on the bottom wall 16 of the channel 15, so that when

the soffit 18 is in position and the grade beam 17 has been poured in the channel 15, a dead air space 30 will be provided below the grade beam 17. In this manner no moisture from the bottom 16 of the channel 15 will be able to come into contact with the grade beam 17 and in the construction of the channel 15, this channel may have the side walls thereof spaced apart a distance equal to or slightly greater than the width of the top wall 25 of the soffit 18, so that the soffit may be easily placed in position and so that grade beam 17 will entirely fill the channel 15. Under certain conditions during the pouring of the concrete forming the grade beam 17 plywood or other suitable form members may be extended into the channel 15 above the soffit 18 and these plywood form members may be gradually withdrawn as the concrete is poured into the channel 15. These plywood form members may be provided in order to prevent the sides of the channel or trench 15 caving in prior to the pouring of the plastic concrete which forms the grade beam 17.

In practice, the soffit 18 is formed of any suitable length and material which may be convenient for proper handling and there may be a number of these soffit members 18 disposed in end abutting relation throughout the length of the trench or channel 15. At the ends of the channels 15 there may be positioned an end soffit 18a which is similar in construction in every detail to the soffit 18 with the exception that an end wall 31 is provided which connects the two side walls 19a and 20a together. With a soffit construction as shown in Figures 1 to 3, inclusive, there will be a considerable economy including a saving of time in the formation of the trench or channel 15 and the elimination of forms below grade and changing beam forms above grade to cheaper wall or curb forms, and in addition the undisturbed earth about the channel 15 will not permit any surface water or moisture to flow downwardly along the outer or inner sides of the grade beam 17. At the present time where form members are put into position within the trench 15 and later removed, it is necessary to fill in the space occupied by the form members and this filled earth being substantially loose will permit surface moisture to flow down the sides of the grade beam and engage beneath the bottom of the grade beam so as to thereby soften the supporting soil and permit the same to be compressed by the weight of the beam and heavily loaded footings resulting in settlement and cracking of the foundation.

In Figures 4 and 5, there is disclosed a modified form of soffit construction which includes a pre-cast soffit which is of substantially H form in transverse section. The soffit shown in Figures 4 and 5 includes vertically disposed side walls 32 and 33, which are connected together by a top wall 34. The outer faces of the side walls 32 and 33 are vertical and parallel and in the present instance the side wall 32 is extended, as at 35, above the upper surface of the top wall 34. In like manner the side wall 33 is extended upwardly as at 36 above the upper surface of the top wall 34. The extensions 35 and 36 have their outer surfaces coincident with the outer surfaces of the lower side wall members 32 and 33, and the grade beam 37 is adapted to be formed above the top wall 33 with a portion 38 of the grade beam disposed between the side wall extensions 35 and 36. The side walls 32 and 33 and the top wall 34 form a dead air space 39 below the top wall 34, so that any moisture seeping down along the sides of the soffit construction and entering the cham-

ber 39 will be prevented from coming into contact with the lower end of the grade beam 37. In addition any swelling action occurring in the bottom 40 of the channel 41 will not exert any vertical pressure on the bottom of the grade beam 37. It will be understood that the soffit construction shown in Figures 4 and 5 may include an end soffit provided with an end wall similar to that shown in Figure 3 for closing the ends of the channel 39.

In Figures 6 and 7 there is disclosed a foundation construction including a soffit 18, which is mounted in a trench or channel 15 formed in the ground and a grade beam 17 extends upwardly from the top wall 25 of the soffit 18. In certain instances it is desirable to form a concrete floor slab 42, which may be cast integral with the grade beam 17. It is also desirable in forming the floor slab 42 that a series of channels be provided beneath the slab 42 so that the swelling of the surface 43 of the ground below the slab 42 will not materially affect the condition of the floor slab 42. In order to provide for the formation of these channels I have provided a plurality of U-shaped channel forming and floor slab supporting members generally designated as 44. These channel forming and floor supporting members 44 include a top wall 45 and vertically disposed side walls 46. A dead air space 47 will be formed between the side walls 46 and the top wall 45. The side walls 46 on their outer sides are provided with a longitudinally extending rib or flange 48 which is positioned in upwardly spaced relation to the lower end of a side wall 46.

Where a number of these floor supporting members 44 are disposed in sidewise abutting relation the adjacent flanges or ribs 48 will be disposed in abutting relation as shown in Figure 6, so as to thereby form a lower dead air space or channel 49 and an upper channel 50. The upper channel 50 is disposed above the ribs 48 and the concrete forming the floor 42 is adapted to extend downwardly into the upper channel 50 thereby forming a connecting rib 51 which rests on a pair of abutting ribs 48 and also ties the adjacent side walls 46 of a pair of adjacent channel members 44 together.

Referring now to Figure 8, there is disclosed a further form of building construction wherein the grade beam 17 is disposed within the channel 15 and entirely fills the channel 15, the soffit in the present instance may or may not be omitted. The floor slab 42a is formed integral with the grade beam 17 and in order to provide suitable channels and supporting means for the floor 42a I have provided a plurality of lower U-shaped supporting members 52, which are initially precast and a pair of endwise spaced apart box-shaped floor supporting members 53 and 54 have their adjacent or confronting ends mounted on the top of the U-shaped member 52. These box-shaped supporting members 53 and 54 are of like construction and include parallel side walls 55, a top wall 56 and vertical end walls 57. An outer supporting member, generally designated as 58, is adapted to support the outer end portion of the box member 53 and abuts against the inner side of the grade beam 17. The supporting member 58 includes a substantially U-shaped member including parallel side walls 59 and 60, a top wall 61 and an inner side wall extension 62, which is formed integral with the inner side wall 59 and extends upwardly from the top wall 61.

The outer end of the supporting member 53

is adapted to rest on the upper edge of the side wall extension 62. The U-shaped member formed by the side walls 59 and 60 and the top wall 61 forms an air channel 63 and the supporting members 53 and 54 form an air channel 64 between the U-shaped lower member 52. The spacing of the adjacent ends of the supporting members 53 and 54 from each other forms a channel 65 within which the plastic concrete forming the slab 42a is adapted to engage so as to tie the supporting members 53 and 54 together and form a reinforcing rib to thereby materially increase the depth of the floor slab and make it self-supporting from one beam to another.

In Figure 9 there is disclosed a further foundation construction using the soffit shown in Figures 4 and 5 for the grade beam 37. The floor slab 42b is cast integral with the grade beam 37 and in order to provide the desired air channels 66 below the slab 42b, I have provided a plurality of sidewise spaced apart U-shaped channel forming members generally designated as 67. These channel forming members 67 are disposed in an inverted position and each member includes vertically disposed side walls 68 and a horizontally disposed top wall 69. As shown in Figure 9, the outermost channel member 67 is disposed in spaced relation to the inner side extension 35 of the soffit and an insulating element 70 is interposed between the outer side wall 68 of the channel forming member 67 and the extension 35. This insulating element 70 is provided in order to prevent direct contact between the beam extension 71 and the prepared surface of the ground.

Between the adjacent side walls of adjacent U-shaped members 67 and 67a, there is also positioned an insulating material or element 72 which is shorter in height than the height of the side walls 68, so that when the plastic material forming the floor slab 42 is poured this material will engage the space 73 between the adjacent U-shaped members 67 and 67a. There may also be provided an air channel forming member generally designated as 74, which is disposed in an inverted position and is interposed between the two adjacent U-shaped members 67a and 67b. The inverted U-shaped member 74 prevents contact between the rib 75, which is formed integral with the slab 42b and the prepared surface of the ground, so that any swelling of the ground below the rib 75 will be absorbed in the air space 76 formed by the inverted U-member 74.

In Figure 10 there is disclosed a grade beam 55 soffit or a floor slab supporting member, generally designated as 77, which is adapted to be interposed between the prepared floor surface and the floor slab. This slab supporting member 77 includes a top wall 78, outer side walls 79 and a bottom wall 80. A pair of intermediate walls or partitions 81 and 82 are connected to the top and bottom walls 79 and 80 respectively thereby forming air channels 83, 84 and 85. Preferably the bottom wall 80 is cut away between the outer side walls 79 and the partitions 81 and 82, so that the lower ends of the side walls 79 and the partitions 81 and 82 will engage on the prepared surface. If larger air channels or less bearing as at 27 and 28, Figure 1, are desired one or more of the partitions 81 and 82 may be removed. Preferably the supporting member 77 is constructed in the form of a hollow tile which may be formed of concrete or baked material.

In Figure 11 there is also disclosed another form of building foundation construction which

includes a grade beam 17 similar to that shown in Figure 1 and a U-shaped soffit 18 at the lower end of the grade beam. A floor slab 86 is adapted to be supported above the prepared surface 87 by means of a plurality of U-shaped precast floor slab supporting members 88. These supporting members 88 include vertically disposed side wall members 89 and a top wall member 90, which is cast or formed integral with the side wall members 89. The floor slab supporting members 88 are disposed in spaced apart relation so as to thereby form air channels 91 between adjacent supporting members 88 and in addition there is formed an air channel 92 between the side members 89 and below the top member 90 of each supporting member 88.

In Figures 12 and 13 there is disclosed a further form of floor slab supporting means which may be associated with the grade beam 17 and a soffit 18. A floor slab 93 is adapted to be supported by a plurality of edge abutting supporting members generally designated as 94. These supporting members 94 include supporting side walls 95, which are of downwardly convergent configuration and which are cast or formed integral with a connecting top wall 96. Laterally extending flanges 97 are formed integral with the top wall 96 so that pairs of these supporting members 94 may be disposed in edge abutting relation with adjacent flanges 97 contacting with each other. In this manner a smooth flat top surface will be provided for the floor slab 93, which will also constitute the lower face of a form for the slab 93. The lower ends of the legs or side wall members 95 are adapted to engage on the upper prepared surface 98 of the ground and there is formed between each pair of legs or supporting walls 95 an air channel 99 and between the side walls of adjacent supporting members 94 there is also formed a smaller channel 100. The legs 95 are shorter in length than the length of the top wall 96 so that there will also be formed transverse air channels.

It will be understood that the grade beam and floor soffits herein shown may be interchanged, one with another as conditions warrant, the arrangements shown being merely illustrative of one use of these soffits.

In Figure 14 there is disclosed a soffit structure similar to that shown in Figure 10 with the soffit 77 mounted in a relatively shallow trench and the grade beam rising from the top wall 78 of the soffit 77. In this form the bottom wall 83 has been retained and the several dead air channels or spaces 83, 84, and 85 are closed by the top and bottom walls 78 and 82 respectively, and the side walls 79 together with the partitions 81 and 82. In Figure 17 there is disclosed a soffit structure similar to that shown in Figure 14, the soffit being designated generally by the numeral 101. This soffit is rectangular in transverse section and includes a top wall 102, a bottom wall 103, side walls 104 and an intermediate partition 104, which divides the interior of the soffit into a pair of dead air chambers 105 and 107. This soffit 101 may be used for engagement on the upper surface of the prepared ground or if desired, it may be positioned within a trench of the desired depth. The grade beam 108 is initially formed of plastic material which engages between conventional forms and the grade beam 108 extends upwardly from the top wall 102.

In Figure 16 there is disclosed a soffit structure 109 which is rectangular in transverse section and is adapted to be mounted in a trench 110.

The soffit 109 includes a top wall 111, a bottom wall 112 and side walls 113. The grade beam 114 is mounted on top of the top wall 111 and the bottom of the grade beam 114 is substantially flush with the prepared surface of the ground.

In Figure 22 there is disclosed a soffit structure generally designated as 115, which is mounted in a trench 116. The soffit 115 is constructed in the form of a truncated triangle in transverse section 10 which has the base 117 uppermost and the smaller end 118 constitutes the bottom wall. The side walls 119 diverge upwardly from the bottom wall 118 and form an interior chamber 120 and also a pair of triangularly-shaped channels or chambers 121 between the outer sides of the side walls 119 and the adjacent faces of the trench 116. The grade beam 122 is partly disposed within the trench 116 and rises upwardly therefrom with the bottom of the grade beam 122 resting on the top wall 117 of the soffit 115.

Referring now to Figure 15 there is disclosed a tubular or hollow soffit structure 123, which is triangularly-shaped in transverse section and is adapted to be disposed in a V-shaped trench 124. The soffit 123 has the base 125 thereof uppermost and the side walls 126 are disposed in downwardly convergent relation. A dead air space 127 is formed within the area encompassed by the top wall 125 and the sides 126.

In Figure 19 there is disclosed a soffit structure 123, which is similar to the soffit shown in Figure 15, but the soffit 123 in Figure 19 is adapted to be mounted in a trench 128, which is rectangular in transverse section and the top wall 125 of the soffit 123 is substantially flush with the prepared surface 129. The grade beam 130 rises from the top wall 125 and is initially cast between the forms which extend upwardly from the precast soffit 123.

In Figure 18 there is disclosed a further modified form of soffit structure generally designated as 131, which is formed substantially semi-circular in transverse section and is positioned in an inverted position so as to form a semi-cylindrical air channel 132. The soffit 131 is adapted to be mounted in a trench 133 and the grade beam 134 is cast or formed on top of the soffit 131.

Referring now to Figure 20, there is disclosed a soffit structure including a pair of cylindrical or tubular soffit members 135 and 136, which are disposed in side-by-side relation and engage within the trench 137. If desired the confronting or adjacent sides of the tubular members 135 and 136 may be cast integral so that the soffit structure 135—136 will be constructed in the form of a double tubular element on top of which grade beam 138 may be formed.

In Figure 21 there is disclosed a soffit structure including a pair of tubular or cylindrical soffit members 139 and 140 which are similar to the soffit members 135 and 136 and engage in a trench 141. A top plate 142 engages on the upper portions of the two soffit members 139 and 140, and if desired may be cast integral with these two tubular soffit members. The grade beam 143 is cast on top of the plate 142.

Referring now to Figure 23 there is disclosed a soffit structure somewhat similar to the soffits shown in Figures 15 and 19, the soffit structure 70 shown in Figure 23 including a pair of triangular-shaped hollow bodies or tubular members 144 and 145, which are disposed with their bases 146 and 147 respectively uppermost and the bases 146 and 148 are connected together by a connecting wall 148, which is preferably formed or cast integrally

with the bases 146 and 147. A grade beam 149 is formed on top of the wall, which includes the bases 146 and 147 and the connecting wall 148.

The soffits shown in Figures 14 to 23 are all of precast concrete material and as shown in these figures these soffits may be used either on top of the prepared surface, partly embedded or extended into a shallow trench or disposed entirely within a trench which is of sufficient depth to permit a portion of the grade beam to be also positioned within the trench.

What I claim is:

1. In a building foundation construction including a monolithic grade beam, means for supporting said beam with the lower edge thereof spaced from the ground, said means comprising a precast U-shaped member having vertical outer sides and disposed in inverted position whereby to form a closed air chamber below said beam.

2. In a building foundation construction including a monolithic grade beam, means for supporting said beam with the lower edge thereof spaced from the ground, said means comprising a precast U-shaped member having vertical outer sides and disposed in inverted position whereby to form a closed air chamber below said beam, and a pair of upwardly extending side members integral with said U-shaped member, the outer sides of said pair of members being coplanar with the first named vertical sides.

3. In combination a precast grade beam supporting member having a U-shaped configura-

tion in transverse section and disposed in inverted position, and a monolithic grade beam resting upon and extending upwardly from said member.

4. The method of forming a grade beam for a building foundation which includes forming a trench or channel in the earth with vertical sides which are spaced apart a distance equal to the thickness of the grade beam, inserting a precast soffit having an inverted U-shape in the bottom of the trench, and pouring plastic concrete on top of the soffit in a quantity sufficient to substantially fill the trench or channel.

5. The method of forming a grade beam for a building foundation which includes forming a trench or channel in the earth with parallel vertical sides which are spaced apart a distance equal to the thickness of the grade beam, inserting a precast soffit of substantially H configuration in transverse section in the bottom of the trench, and pouring plastic concrete on top of the soffit in a quantity sufficient to substantially fill the trench and also to fill the upwardly opening portion of the soffit.

6. In combination, a precast grade beam supporting member having the configuration of an H in transverse section, said member being positioned with the opposite parallel sides thereof vertical to thereby form upper and lower channels, and a grade beam formed of initially plastic material engaging in said upper channel and rising therefrom.

HERBERT J. VON ROSENBERG.
